(57) **CLAIM**

The ornamental design for an LED light fixture body, as shown and described.

DESCRIPTION

FIG. 1 is a perspective view of the LED light fixture body, showing my new design;

FIG. 2 is a front elevation thereof;

FIG. 3 is a right side elevation thereof, the side opposite being a mirror image;

FIG. 4 is a rear elevation view thereof;

FIG. 5 is a partial sectional view taken along line 5-5 of FIG. 4 where the side panel is removed, and the inside structures are omitted;

FIG. 6 is a top plan view, the side opposite being a mirror image; and,

FIG. 7 is a right side elevation when the LED light fixture body is rotated.

The portions of the claimed design shown in broken lines form no part of the claimed design. The front surface with oblique line shadings in FIGS. 1 and 2 is illustrated as being transparent and an internal structure is omitted. The line shading in FIG. 7 is used to indicate portions of the structure illustrated in FIG. 5.
